UNITED STATES PATENT OFFICE

GEORGE W. BAUGHMAN, OF EDGEWOOD BOROUGH, PENNSYLVANIA, ASSIGNOR TO THE UNION SWITCH & SIGNAL COMPANY, OF SWISSVALE, PENNSYLVANIA, A CORPORATION OF PENNSYLVANIA

TRACKWAY APPARATUS FOR AUTOMATIC TRAIN-CONTROL SYSTEMS

Application filed November 28, 1928. Serial No. 322,455.

My invention relates to trackway apparatus for an automatic train control system in which energy is at times supplied to the trackway for the control of apparatus carried on a train.

5 I will describe two forms of trackway apparatus embodying my invention, and will then point out the novel features thereof in claims.

10 In the accompanying drawing, Fig. 1 is a diagrammatic view illustrating one form of trackway apparatus embodying my invention. Fig. 2 is a view showing a modified form of the apparatus illustrated in Fig. 1 and also embodying my invention.

15 Referring first to Fig. 1, the reference characters 1 and 1^a designate the track rails of a stretch of railway track over which traffic normally moves in the direction indicated by the arrow. These rails are divided, by means of insulated joints 2, to form a plurality of successive track sections A—B, B—C, etc. Each track section is provided with a track circuit comprising a battery D connected 25 across the rails adjacent one end of the section, and a track relay designated by the reference character R with a distinguishing exponent connected across the rails adjacent the opposite end of the section.

30 Point B is at the entrance of "train control territory" by which I mean that the portion of track to the right of this point is provided with apparatus not shown in the drawing for controlling governing means on the train in accordance with traffic conditions.

35 Traffic entering train control territory is governed by a trackway signal designated by the reference character S and located adjacent point B. As here shown the signal S is 40 a light signal comprising two units 50 and 51 arranged when lighted to indicate stop or proceed, respectively.

45 Located adjacent point B is a trackway loop designated by the reference character L, which as here shown comprises conductors located in the trackway parallel to the track rails and adapted when supplied with periodically interrupted current to cut the train carried portion of the train control system into 50 service. That is to say, if the trackway loop

L is supplied with periodically interrupted current the train carried portion of the train control system of a train passing the loop will be conditioned so that when the train enters the train control territory to the right of 55 point B the train will thereafter be controlled in accordance with the condition of the trackway apparatus.

The supply of current to the trackway loop L is controlled by a code transmitter designated in general by the reference character K and comprising an armature 4 which is arranged to be swung alternately into engagement with two fixed contacts 4^a and 4^b when the code transmitter is energized. When relay R¹ is de-energized, as when section A—B is occupied by a train, current is supplied to code transmitter K over back contact 3 of relay R¹, from terminals X and Y of a suitable source of alternating current not shown in the drawing. When a train enters section A—B, therefore, and de-energizes relay R¹, the code transmitter K is set into operation so that contacts 4—4^a and 4—4^b are operated alternately. Each time contact 4—4^a is closed, 70 current flows from terminal X, over front contact 4—4^a of code transmitter K and primary 5 of a transformer T to terminal Y. The secondary 6 of transformer T is connected through primary 7 of transformer G 75 directly with the trackway loop L. It follows, therefore, that when the code transmitter is being operated, periodically interrupted current is supplied to the trackway loop L. The secondary 8 of transformer G is connected, through a rectifier J^c, with the winding of a slow releasing relay P^c, so that this relay holds its front contacts closed continuously when the code transmitter K is operated. 80

The code transmitter K also controls an auxiliary circuit including the primary 9 of a transformer H, it being noticed that each time contact 4—4^b of the code transmitter is closed, that is, during the interruptions between successive impulses of current supplied to the trackway loop L, current is supplied from terminals X and Y to the primary 9 of transformer H. The secondary 10 of transformer H is connected, through a rectifier J^H, 95 100

with the winding of a slow releasing relay P^H , so that relay P^H holds its front contacts closed continuously when code transmitter K is being operated.

5 The signal S is controlled in part by relays P^G and P^H so that when either of these relays is de-energized a circuit is completed from a source of energy such as battery Q, over back contact 14 of relay P^G or back contact 15 of relay P^H , and unit 50 of signal S back to battery Q. When this circuit is closed, the signal S indicates stop. If, however, the code transmitter K is being operated, relays P^G and P^H are both energized as explained here-
10 before, and if relay R^2 is energized current flows from battery Q, over front contact 11 of relay P^G , front contact 12 of relay P^H , front contact 13 of relay R^2 , unit 51 of signal S and back to battery Q. Under these conditions, 15 unit 51 of signal S is lighted to indicate proceed. If relay R^2 is de-energized when a train enters section A—B, the circuit just traced for unit 51 of signal S is interrupted, and a circuit is then completed for unit 50 of signal 20
25 S over front contacts of relays P^G and P^H and back contact 13 of relay R^2 . It follows, therefore, that signal S can indicate proceed only if relay R^2 is energized and relays P^G and P^H are both energized. If, therefore, 30 the code transmitter fails to operate, or if the circuit for the trackway loop L is for any reason interrupted, one or both of relays P^G and P^H will be de-energized and signal S will then indicate stop, independently of traffic 35 conditions in advance, so that the operator of the train passing signal S will be informed that the train carried portion of the train control system is not conditioned to place the train under the influence of the train control 40 system.

Referring now to Fig. 2, the signal S^1 , as here shown, is of the semaphore type and is controlled by a manually operable lever U which may be located at a point remote from 45 the signal, as for example, in an interlocking cabin. Operatively connected with the lever U is a segment 37 which co-operates with a dog 38 controlled by a magnet M for at times controlling movements of the lever U. As 50 shown in the drawing, the lever U occupies its normal position, and normal contact 19 is closed. If the lever is moved in a clockwise direction toward its reverse position, contact 19 opens. The motion of the lever is arrested, 55 however, by co-operation of dog 38 and segment 37 unless magnet M is energized. If magnet M is energized to release the segment 37, the lever U may be moved to its full reverse position in which case reverse contact 60 65 40 is closed. As shown in the drawing, the circuit for signal S^1 is open, so that this signal indicates stop. Furthermore, the code transmitter K is at rest so that relays P^G and P^H are both deenergized. A circuit is now closed, however, for an approach relay W

which circuit may be traced from battery Q, over wires 18 and 18^a, normal contact 19 of lever U, wire 20, winding of relay W, and wires 21, 23 and 24, back to battery Q.

I will now assume that the operator wishes to clear signal S^1 . He first moves lever U away from its normal position, until the motion of the lever is arrested by the dog 38 and segment 37. In this position of lever U, the normal contact 19 is open, and the circuit for relay W is therefore interrupted, so that this relay becomes deenergized. A circuit is then completed from terminal X, over back contact 25 of relay W, wires 26 and 27, and winding of transmitter K to terminal Y. The code transmitter is therefore set into operation and current flows from terminal X, over back contact 25 of relay W, wires 26, 28 and 29, and thence over contacts 4—4^a and 4—4^b of code transmitter K to transformer H and T as described in connection with Fig. 1. The trackway loop L is therefore supplied with periodically interrupted current and relays P^G and P^H are held closed. As soon as relays P^G and P^H become energized, the operator may energize magnet M of the lever U to release the latch, by closing the manually operable contact 16. Current then flows from battery Q, over wire 31, circuit controller 17 operated by signal S, wire 32, front contact 12 of relay P^H , wire 33, front contact 11 of relay P^G , wire 34, contact 16, wire 35, magnet M, and wires 36, 23 and 24 back to battery Q. Current supplied over this circuit energizes magnet M and lifts dog 38 out of engagement with segment 37. The operator may then move lever U to its reverse position, thereby closing contact 40. The magnet M becomes de-energized as soon as contact 16 is released. When contact 40 closes, current flows from battery Q, over wires 18 and 39, reverse contact 40 of lever U, wire 41, front contact 13 of relay R^2 , wire 42, operating mechanism of signal S^1 , and wires 43 and 24 back to battery Q. Signal S^1 then displays a proceed indication.

It should be pointed out that an auxiliary circuit is provided for supplying energy to the code transmitter K over back contact 3 of relay R^1 . The purpose of this arrangement is to set the code transmitter K into operation when a train enters section A—B even though lever U is not moved away from its normal position in an attempt to clear signal S^1 . It will be manifest from the foregoing that the lever U can be moved to its reverse position for clearing signal S^1 only if the trackway loop L is being supplied with periodically interrupted current by the code transmitter K so that relay P^G and P^H are both energized.

If the operator wishes to restore signal S^1 to the stop position, he moves lever U away from its reverse position, until the lever is arrested by segment 37 and dog 38, thereby interrupting the circuit for signal S and re-

storing the signal to stop. After circuit controller 17 has become closed, the operator may close contact 16, thereby picking up magnet M if relays P^G and P^H are both energized. Dog 38 is then lifted out of engagement with segment 37 and the lever may be restored to its normal position in which it is shown in the drawing. Under these conditions, relay W will be energized, and if section A-B is unoccupied so that relay R¹ is

5 energized, the code transmitter K will be stopped and the supply of periodically interrupted current to the trackway loop L will be discontinued.

10 15 Although I have herein shown and described only two forms of trackway apparatus embodying my invention, it is understood that various changes and modifications may be made therein within the scope of the appended claims without departing from the spirit and scope of my invention.

20 Having thus described my invention, what I claim is:

1. Trackway apparatus for an automatic train control system comprising a trackway loop located at the entrance to train control territory and adapted when energized to cut the train carried portion of the system into service, a signal governing the entrance of 25 trains into said territory, a lever for controlling said signal, and means for controlling said lever by current flowing in said loop.

30 35 40 2. Trackway apparatus for an automatic train control system comprising a trackway loop located at the entrance to train control territory and adapted when energized to cut the train carried portion of the system into service, a signal governing the entrance of trains into said territory, a lever for controlling said signal, an electric lock for preventing said lever from being moved to clear the signal unless the lock is energized, and means for energizing said lock if and only if said loop is energized.

45 50 55 3. Trackway apparatus for an automatic train control system comprising a trackway loop located at the entrance to automatic train control territory and adapted when energized to cut the train carried portion of the system into service, a relay arranged to be energized when and only when said loop is energized, a signal governing the entrance of trains into said territory, a lever for controlling said signal, and means for controlling said lever by said relay.

60 65 4. Trackway apparatus for an automatic train control system comprising a trackway loop located at the entrance to automatic train control territory and adapted when energized to cut the train carried portion of the system into service, a transformer having a primary included in circuit with said loop, a relay receiving energy from the secondary of said transformer, a signal governing the entrance of trains into said territory, a lever for con-

trolling said signal, an electric lock for preventing said lever from being moved to clear the signal unless the lock is energized, and means for energizing said lock if and only if said relay is energized.

70 5. Trackway apparatus for an automatic train control system comprising a trackway loop located at the entrance to automatic train control territory and adapted when supplied with periodically interrupted alternating current to cut the train carried portion of the system into service, a slow releasing relay arranged to remain continuously closed while said loop is supplied with periodically interrupted current, a signal governing the entrance of trains into said automatic train control territory, and means for controlling said signal by said relay.

75 6. Trackway apparatus for an automatic train control system comprising a trackway loop located at the entrance to automatic train control territory and adapted when supplied with periodically interrupted alternating current to cut the train carried portion of the system into service, a slow releasing relay arranged to remain continuously closed while said loop is supplied with periodically interrupted current, a signal governing the entrance of trains into said automatic train control territory, a lever for controlling said signal, and means for controlling said lever by said relay.

80 85 90 95 100 105 7. Trackway apparatus for an automatic train control system comprising a trackway loop located at the entrance to automatic train control territory and adapted when supplied with periodically interrupted alternating current to cut the train carried portion of the system into service, a slow releasing relay arranged to remain continuously closed while said loop is supplied with periodically interrupted current, a signal governing the entrance of trains into said automatic train control territory, a lever for controlling said signal, an electric lock for preventing said lever from being moved to clear the signal unless the lock is energized, and means for energizing said lock if and only if said relay is energized.

110 115 120 125 120 130 8. Trackway apparatus for an automatic train control system comprising a trackway loop located at the entrance to train control territory and adapted when supplied with periodically interrupted alternating current to cut the train carried portion of the system into service, an auxiliary circuit, a code transmitter having a front contact which is periodically closed while the transmitter is in operation and a back contact which is closed each time the front contact is open, means including said front contact for supplying alternating current to said loop, means including said back contact for supplying alternating current to said auxiliary circuit, two slow releasing relays one re-

ceiving energy from said loop and the other from said auxiliary circuit and each arranged to remain closed while said code transmitter is in operation, a signal governing the entrance of trains into said train control territory, and means for controlling said signal by said relays.

9. Trackway apparatus for an automatic train control system comprising a trackway loop located at the entrance to train control territory and adapted when supplied with periodically interrupted alternating current to cut the train carried portion of the system into service, an auxiliary circuit, a code transmitter having a front contact which is periodically closed while the transmitter is in operation and a back contact which is closed each time the front contact is open, means including said front contact for supplying alternating current to said loop, means including said back contact for supplying alternating current to said auxiliary circuit, a first rectifier receiving current from said loop, a second rectifier receiving current from said auxiliary circuit, two slow releasing direct current relays receiving current from said first and second rectifiers respectively, a signal governing the entrance of trains into said train control territory, and means for controlling said signal by said relays.

10. Trackway apparatus for an automatic train control system comprising a trackway loop located at the entrance to train control territory and adapted when supplied with periodically interrupted alternating current to cut the train carried portion of the system into service, an auxiliary circuit, a code transmitter having a front contact which is periodically closed while the transmitter is in operation and a back contact which is closed each time the front contact is open, means including said front contact for supplying alternating current to said loop, means including said back contact for supplying alternating current to said auxiliary circuit, two slow releasing relays one receiving energy from said loop and the other from said auxiliary circuit and each arranged to remain closed while said code transmitter is in operation, a signal governing the entrance of trains into said train control territory, and means for preventing said signal being changed from the stop indication to a proceed indication unless both of said relays are closed.

11. Trackway apparatus for an automatic train control system comprising a trackway loop located at the entrance to train control territory and adapted when supplied with periodically interrupted alternating current to cut the train carried portion of the system into service, an auxiliary circuit, a code transmitter having a front contact which is periodically closed while the transmitter is in op-

eration and a back contact which is closed each time the front contact is open, means including said front contact for supplying alternating current to said loop, means including said back contact for supplying alternating current to said auxiliary circuit, two slow releasing relays one receiving energy from said loop and the other from said auxiliary circuit and each arranged to remain closed while said code transmitter is in operation, a signal governing the entrance of trains into said train control territory, a lever for controlling said signal, an electric lock for preventing said lever being moved to clear the signal unless the lock is energized, and means for energizing said lock if and only if both of said relays are closed.

12. Trackway apparatus for an automatic train control system comprising a trackway loop located at the entrance to train control territory and adapted when supplied with periodically interrupted alternating current to cut the train carried portion of the system into service, an auxiliary circuit, a code transmitter having a front contact which is periodically closed while the transmitter is in operation and a back contact which is closed each time the front contact is open, means including said front contact for supplying alternating current to said loop, means including said back contact for supplying alternating current to said auxiliary circuit, two slow releasing relays one receiving energy from said loop and the other from said auxiliary circuit and each arranged to remain closed while said code transmitter is in operation, a signal governing the entrance of trains into said train control territory, a lever for controlling said signal, an electric lock for preventing said lever being moved far enough from the stop position to clear the signal, unless the lock is energized, means for setting said code transmitter into operation upon a preliminary movement of said lever away from the stop position, and means for energizing said lock if and only if both of said relay are closed.

13. Trackway apparatus for an automatic train control system comprising a trackway loop located at the entrance to train control territory and adapted when supplied with periodically interrupted alternating current to cut the train carried portion of the system into service, a code transmitter for supplying periodically interrupted current to said loop, a first slow releasing relay energized when such current is being supplied to said loop, a second slow releasing relay energized while said current is interrupted, and a signal governing the entrance of trains into said train control territory and controlled by said two relays.

14. Trackway apparatus for an automatic train control system comprising a trackway loop located at the entrance to train control

territory and adapted when supplied with periodically interrupted alternating current to cut the train carried portion of the system into service, an auxiliary circuit, a code transmitter having a front contact which is periodically closed while the transmitter is in operation and a back contact which is closed each time the front contact is open, means including said front contact for supplying alternating current to said loop, means including said back contact for supplying alternating current to said auxiliary circuit, two slow releasing relays one receiving energy from said loop and the other from said auxiliary circuit and each arranged to remain closed while said code transmitter is in operation, a signal governing the entrance of trains into said train control territory and controlled by said relays and by traffic conditions.

In testimony whereof I affix my signature.
GEORGE W. BAUGHMAN.
